[57] CLAIM

The ornamental design for a thong panty liner, as shown and described.

DESCRIPTION

FIG. 1 is a perspective view of the thong panty liner in accordance with the present invention showing separation of the leading edge;

FIG. 2 is a bottom plan view thereof without edge separation;

FIG. 3 is a top plan view thereof without edge separation;

FIG. 4 is a rear elevation view thereof showing the separated components together;

FIG. 5 is a front elevation view thereof; and,

FIG. 6 is a side elevation view thereof, the opposite side elevation view being a mirror image.
